UNITED STATES PATENT OFFICE.

EDWARD PROBERT, OF SAN FRANCISCO, CALIFORNIA.

CUPOLA-FURNACE HAVING SECTIONAL WATER-JACKETS.

SPECIFICATION forming part of Letters Patent No. 320,586, dated June 23, 1885.

Application filed January 7, 1884. (No model.)

To all whom it may concern:

Be it known that I, EDWARD PROBERT, of the city and county of San Francisco, and State of California, have invented an Improvement in 5 Cupola - Furnaces having Sectional Water-Jackets; and I hereby declare the following to be a full, clear, and exact description thereof.

My invention relates to a new and useful blast furnace, designed more especially for the 10 smelting of silver-lead ores, but equally adapted for working, with the addition of suitable fluxes, all other ores containing silver and gold.

My invention consists, mainly, in such an arrangement and construction of tuyeres as enables me to largely increase the capacity of the 15 furnace, and in a peculiar water jacket or trough, which I term a "hydrocycle," surrounding the region of fusion, and consisting of a circular series of independent and separately-removable water-cells suitably joined.

It consists also in various details of construction, embracing the tuyeres, the hydrocycle, the foundation, the shell and its supports, and other minor features, all having in view the 20 general perfection of the furnace, and all of which I shall hereinafter fully describe by reference to the accompanying drawings.

Figure 1 is a perspective view of my ore-smelting furnace. Fig. 2 is a vertical section on the line *xx*, Fig. 3. Fig. 3 is a horizontal section, the upper portion (marked 1) being one half of the circumference of the furnace, taken on the line *yy*, Fig. 2, while the lower portion (marked 2) (the other half of the furnace) 35 is a section on the line *zz*, Fig. 2. Fig. 4 is an enlarged perspective view of one of the cells or compartments of the hydrocycle and a portion of another, showing the means for securing them together. Fig. 5 is a vertical longitudinal section showing the long tuyeres *P.*

The special objects or advantages which I claim for the furnace are its large smelting capacity, the facility with which it can be repaired even while in operation, and the facility, 45 generally, with which the entire operation may be carried on. The first of these advantages arises from overcoming, as I shall show, the disadvantages in the ordinary furnaces. It is well known that in the construction of pressure blast-furnaces of the ordinary type the diameter should never exceed twice the "throw"

of the blast—that is, twice the distance to which the blast penetrates the charge, or, say, from thirty to forty inches. This necessity limits the smelting capacity of the furnace, so that the 55 daily production rarely exceeds from twenty to thirty tons. My invention renders it possible to increase the diameter of the furnace, and therefore its productive (or smelting) capacity, more than twofold without materially 60 increasing the cost of construction, while the running expenses are reduced to a minimum.

The second advantage arises from the peculiar construction of the hydrocycle, the elements or independent cells of which are so 65 fitted to place and united as to render it possible for each to be cleaned while in place, or taken out for repairs while the furnace is in actual operation, with the least possible difficulty and in the shortest length of time. 70

The last advantage results from the general construction of all the parts, and will be better seen as the description progresses.

The bottom of the furnace consists of a circular wall, *A*, of fire-rock or fire-brick, the top 75 of which rises three feet above the level of the smelting-floor, and is carried downward an equal distance below the surface of the earth or floor, where it rests on a cast-iron foundation-plate, *B*, two and one-half inches thick, 80 and having a curb, *b*, running round its edge, which holds in position a series of curvilinear cast-iron slabs, *C*, each six feet in height, three feet in curvilinear measurement, and two and a half inches thick. These are bolted and 85 clamped together at their upper ends, and further strengthened by having two strong circular iron bands, *c*, passed completely round them, so as to form an envelope around the masonry or fire-brick wall. Within this wall 90 is formed the smelting hearth or crucible *D* of the furnace, (containing, usually, from ten to fifteen tons of red-hot lead,) and which is constructed of the usual refractory furnace materials, consisting of fire-bricks, fire-clay, sand, 95 and "brasque," (clay and coke-dust beaten together,) out of which last material the upper surface of the crucible is molded, so as to assume a bowl-shaped form to hold the lead.

A two-inch hole, *e*, having a spout, *E*, at 100 its upper and outer end, is drilled obliquely downward from the outside of the furnace

through the iron casing, the fire-brick wall, and the composition within, so as to strike the bottom of the bowl-shaped cavity, and through this the red-hot lead rises under the pressure 5 of the charge, and the accumulating metal when the furnace is in action, till it runs out at the spout and is received in a pot placed beneath. The chief novelty in this lower part 10 of the furnace (or base) is the working front F, the shape of which is obtained by drawing two tangents to the circle of the base at the extremities of its front quadrant, extending them until they meet, and then truncating the right angle formed at such a distance from the 15 angle as will give a working front of about three and a half feet long, projecting outward about one foot beyond the general curvature of the base.

The general form thus obtained, though 20 parting very little from that of a circle, is much more convenient in use, the projecting front giving the extra depth required for working the furnace and offering special facilities for affixing and changing the slag-spout f and 25 speiss or matte spout f'. This peculiar form of working front is also advantageous in that it allows greater facility in bracing the entire wall, as the encircling strips curve to a better advantage and bind the whole in a better 30 manner than if a straight projecting front were used.

Resting upon the upper rim of the wall of fire rock or brick, which I have described, is the hydrocycle, which I designate as an entirety by G. It consists of a series of (nine, 35 more or less,) independent water-tight iron cells or compartments, g, of curvilinear form, locked rigidly together by means of bolts and cutters, (in a manner presently to be described,) so as to form an annular cellular 40 trough, through which the water circulates, entering under pressure near the bottom of each cell, through pipes h, from an encircling supply-pipe, H, above, and being discharged 45 over the top edge of the outer side of each into a launder or gutter, I, passing around the furnace.

The special details of construction of the 50 several segmental compartments of the hydrocycle to be pointed out, and the manner of bolting them together, are as follows: Each segment is constructed, preferably, of three-eighths-inch boiler-plate, the sheet forming the inner wall being of the best flange-iron, capable of having its four edges turned back all 55 round to the depth of three inches at least, to receive the single curved piece forming the front and sides, the bottom piece, and the apron or top piece, g', which is applied at a 60 considerable slope toward the interior of the furnace and only partly closes the top, whereby a space four inches wide and running the full length of the compartment is left open for cleaning it out from time to time and removing the "fur" apt to be deposited by 65 the water, Fig. 4. The several sheets are riveted together, so as to form a curvilinear-

ear segmental water-tight cell, about three feet deep, two feet in circular outside measurement, and one foot between the inner and outer walls at the top, tapering downward to eight inches at the bottom. Each segmental cell is provided with a T-pipe coupling, g', on the outside, by means of which a tubular connection, k, may be made between the cells, 70 thus insuring a constant level and free circulation of the water in and through all the cells. Each cell is further provided with a lip or spout, l, through which the overflow or waste water passes to the launder. 75

In order to connect the several segmental cells together and form the rigid trough or hydrocycle, a flat bar of iron, m, about three inches wide and one inch thick, is bolted horizontally on the outer side of each, following 80 its contour. The ends of the bars are turned outward two inches at a right angle, and a hole is made in each to receive an inch-bolt, m', which is slotted to receive in its turn a "cutter" or wedge-shaped key, m², Fig. 4. When 85 these several cutters or wedges are driven home, the ends of all the short curved bars are forcibly drawn toward each other and the bars united into a circle, which, tightening on the water-compartments, locks them securely 90 together, forming a rigid whole, the hydrocycle having the form of a frustum of an inverted hollow cone, the interior surface of 95 which has a slope of about one in eight, corresponding to the general interior slope of the 100 furnace.

The cutters and bolts being removable at pleasure, any compartment of the hydrocycle can be readily detached and withdrawn from its place, in case of its leaking or needing repairs, and another substituted for it, without disturbing the rest, the whole operation not occupying more than half an hour, instead of causing the loss of entire days and necessitating the suspension of smelting operations. 110

That compartment of the hydrocycle which faces the working front of the furnace does not extend downward as far as the rest, a space of about six inches being left beneath it to allow of the raking out of the scoria occasionally from the interior. Moreover, this particular compartment, instead of resting on the masonry of the lower part of the furnace, like the rest, is suspended between the two adjoining ones at a slightly higher level by the two 115 overflow-spouts o, with which it is provided, and by which also it discharges the waste water into the two adjoining compartments, instead of into the launder, which it is not found convenient to carry completely round the 120 working front, Fig. 1.

Through certain of the cells of the hydrocycle are inserted the long blast-tuyeres P, consisting of pipes having a surrounding water-jacket, P', in which a constant circulation 130 of water is maintained by means of the short feed-pipes p, supplied from a pipe, Q, below, and the discharge-pipes p', emptying their contents into the launder. These tuyeres project

into the furnace two feet or more, or as far as the dotted circle in Fig. 3, which may be taken as representing the sectional interior area of a circular blast-furnace of average size—or, 5 say, thirty-six inches in diameter.

By projecting a tuyere through the lining of the furnace and into its region of fusion I am enabled to increase the diameter of the furnace; but in order to maintain such an inwardly-projecting tuyere it must either be of material refractory enough to withstand the heat, or it must be a water-tuyere. I prefer the latter, but with such a long tuyere, and with so much weight on its inner end, it be- 10 comes essential to provide a firm support in the body of the furnace through which it passes. If it passed through the ordinary shell of the furnace, whether lined with refractory material or not, it would soon lose its sup- 15 port by reason of burning away of the refractory lining, and the inner end of the tuyere would soon fall out of position; but by my construction this danger is avoided because the water-jackets withstand the action of the 20 heat, and there remains a firm support for the inwardly-projecting tuyere—an important feature in my furnace.

Through the remaining cells of the hydro- 30 cycle are let short blast-tuyeres, *q*, which do not project within the furnace at all, Fig. 3.

R are the blast-pipes having their nozzles inserted in the open center of the long tuyeres *P* and in the short tuyeres *q*. These are supplied with air under pressure through the flexible pipes or tubes *r* from a wind-chamber, *S*, above.

For the short tuyeres *q* the water-cells of the hydrocycle serve as water-tuyeres, so that they will not be burned out. 40 It will be perceived that the air entering the furnace through the long tuyeres will be discharged within the area of the dotted circle, while that entering through the shorter ones *q* will be discharged within the curvilinear 45 ear spaces lying between the several pairs of long tuyeres and the sides of the hydrocycle. While, therefore, the former set of tuyeres supply air for the smelting of the portion of the charge lying within the area of the dotted 50 circle, the latter set, opening directly on the inside of the several compartments, convey it to the portions lying within the curvilinear spaces immediately in front of them, and thus 55 over the whole area of the furnace, and the effect of two furnaces working, as it were, one within the other, is produced. It will be readily seen from this that the capacity of my furnace is largely increased.

60 It only remains to describe the shell *T*, or upper portion of the furnace, which has the shape of a truncated inverted cone, and which rises about twelve feet above the hydrocycle to the feed-floor above, (where it receives the ore and fuel—the charge,) and is surmounted by a dome and stack leading to the flue, which parts I

have herein deemed it unnecessary to show. The outer tunic or casing of this shell is of one-eighth to three-sixteenths inch sheet-iron, and the lining of common bricks, except for a 70 distance of two feet from the bottom, where the shell takes a reverse slope (designated by *U*) to the top of the hydrocycle, and for this portion fire-bricks are used. The shell is supported indirectly by cast-iron pillars *V*, and 75 no part of the weight is borne by the hydrocycle, which is left perfectly free, a space being left in which a layer of brick, *t*, supported upon the apron of the water-cells, is placed, Fig. 2. 80

The novelty to be noted about the upper part of the furnace is the wind-chamber *S*, which, instead of being made of thin galvanized iron or zinc, as is usual, and serving merely for the distribution of the blast, is made 85 of iron-plate, or stout sheet-iron, or cast-iron, and converted into a hollow girder, in section a right-angled triangle, which, encircling the shell beneath a flange, *s*, receives its weight and transfers it to the cast-iron pillars, upon 90 which it rests and which rise from the foundation-plate. By thus making the girder triangular instead of rectangular sufficient strength is obtained with very much less material. This girder wind-chamber receives the blast 95 from suitable blowers through a ten-inch aperture and distributes it to the blast pipes or tuyeres.

The water which is supplied to the tuyeres and hydrocycle becomes boiling hot, and 100 usually deposits a considerable amount of calcium sulphates and carbonates on the inner surface, which tends to cause the iron to burn out, and hence the great importance of leaving the water-cells open at the top, so that the 105 deposit or fur from the water may be readily removed.

The advantage gained by the reverse slope *U* of the shell is that it gives an enlargement for the expansion of the gases from the charge, 110 and more time is gained for their proper operation.

As the ore or charge lies in the throat, it is compact, but lower down the gases have a better opportunity to get at all the particles. 115

The furnace thus far described is of circular form and of the diameter of seven feet, and is capable of smelting from fifty to sixty tons of ore daily; but the principle explained by which the capacity is increased is applicable to the 120 construction of a still larger furnace. For retaining the diameter of seven feet, (which has been found the most advantageous in practice,) all that is necessary is to separate the two semicircles into which the plan of the hydrocycle may be supposed to be divided by a space, say, equal to the semi-diameter of the furnace, or three and a half feet, and then to introduce into the openings on either side a pair of additional cells of rectangular shape, 125 (not curvilinear,) when the furnace will be converted into an oblong one with circular heads 130

or ends capable of smelting from eighty to one hundred tons daily, which is the capacity of one now in actual use, and which has even exceeded the highest production named.

5. I am aware that projecting working fronts for furnaces are not new; but these have been heretofore added to the base in a manner to form an angle with its curvilinear or polygonal periphery, and I do not, therefore, claim such broadly; but I claim only my tangential front, in connection with the curvilinear base, envelope, supporting-plate, and inclosing-bands, as I have described.

I am also aware that sectional water-jackets have been used.

15 I am further aware that in iron blast-furnaces and foundry cupola-furnaces for melting cast-iron, tuyeres or pipes covered with refractory material have been projected within the lining; but these have been projected into the bosh of the furnace, and have been arranged in various horizontal planes and in groups.

Having thus described my invention, what I claim as new, and desire to secure by Letters 25 Patent, is—

1. In an ore blast-furnace, the curvilinear wall A, in which the crucible is formed, said wall having a projecting working front, F, the sides of which are tangential to the circle of 30 the wall, in combination with the bands c, passing completely around wall A and the front F, and bolted thereto, substantially as herein described.

2. In an ore blast-furnace, the curvilinear wall A, of fire-rock or fire-brick, in which the crucible is formed, said wall having a projecting working front, F, the sides of which are tangential to the circle of the base, and the series of iron slabs C, fitted to and encircling 40 said wall and front, in combination with the iron bands c, passing completely around said slabs and bolted thereto, whereby an envelope is formed around the masonry or fire-brick wall, substantially as herein described.

45 3. In an ore blast-furnace, the curvilinear wall A, in which the crucible is formed, said wall having a projecting working front, F, the sides of which are tangential to the circle of the wall, and the series of iron slabs C, fitted 50 to and encircling said wall and front, in combination with the foundation-plate B, embedded in the earth, and having a curb, b, within which the wall A and slab C rest, and the iron bands c, passing completely around said slabs 55 and bolted thereto, substantially as herein described.

4. In an ore-smelting furnace, the annular water-jacket or hydrocycle G surrounding and in direct contact with the region of fusion, said 60 hydrocycle being constructed of a single series of independent and separately-removable cells or compartments, in combination with means by which said cells are bound and clamped together into a rigid whole, consisting of the bars m bolted to each, and having outwardly-turned perforated ends, the slotted bolts m',

and the cutters m², substantially as herein described.

5. In an ore-smelting furnace, the annular water-jacket or hydrocycle G surrounding the region of fusion, said hydrocycle consisting of the series of independent and separately-removable curvilinear water-tight cells or compartments g bound together, and each having a T-coupling in its outer wall, whereby a water-connection may be made throughout the series, a water-inlet through pipes h, and a discharge over its top, and the encircling launder I, substantially as herein described.

6. In an ore-smelting furnace, the annular water-jacket or hydrocycle surrounding the region of fusion, and consisting of independent and separately-removable water-tight cells bound together, one of which is slightly raised above the adjoining ones, top and bottom, and discharges therein from its top, in combination with the wall A upon which the hydrocycle rests, and having its working front in communication with the crucible under said specified section, substantially as and for the 90 purpose herein described.

7. In an ore-smelting furnace, the annular water-jacket or hydrocycle G surrounding and in direct contact with the region of fusion, and consisting of the independent and separately-removable water-tight cells g, in combination with the bars m, bolted to each cell, the slotted bolts m', and cutters m² by which said cells are bound together into a rigid whole, the encircling pipe H, and the short 100 pipes h by which the cells are supplied with water, the T-coupling g² and tubular connection k by which a water-communication between the several cells is effected, and the lip or spout l and encircling launder I by which 105 the water is carried off, all arranged and operating substantially as herein described.

8. In an ore-smelting furnace having one set or series of blast-tuyeres at the region of fusion and a diameter greater than twice the throw 110 of the blast from said tuyeres, one or more sets or series of supplementary or additional blast-tuyeres in the same horizontal plane as the first set and alternating therewith, said additional tuyeres projecting within the furnace a sufficient distance to throw their blasts into the spaces which lie nearer the center or beyond the limit of the throw of the blast from the first set or series of tuyeres, the blasts from which are directed to the spaces lying 115 between the supplementary tuyeres, substantially as herein described.

9. In an ore-smelting furnace having one set or series of blast-tuyeres at the region of fusion opening through and protected by the 125 water-jacket of the furnace, said furnace having a diameter greater than twice the throw of the blast from said tuyeres, one or more sets or series of supplementary or additional blast-tuyeres in the same horizontal plane as 130 the first set and alternating therewith, said additional tuyeres projecting within the fur-

nace a sufficient distance to throw their blasts into the spaces which lie nearer the center or beyond the limit of the throw of the blast from the first set or series of tuyeres, and a water-jacket or casing surrounding each of said inwardly-projecting tuyeres, substantially as herein described.

10. In an ore-smelting furnace having a water-jacket or hydrocycle surrounding the region of fusion, the short blast-tuyeres *q*, let through said water-jacket and flush with the inner wall, in combination with the long tuyeres *P* in the same horizontal plane and alternating with tuyeres *q*, said long tuyeres 15 projecting into the furnace and having a surrounding water space, *P'*, and means for supplying said space with water, substantially as herein described.

11. In an ore-smelting furnace, the hydrocycle *G* surrounding the region of fusion, and consisting of independent and separately-removable cells or compartments *g*, bound together and each having an apron or top piece, *g'*, partially inclosing the top and sloping to 25 the interior, in combination with the shell *T*, supported by pillars *V* above, and not resting on the hydrocycle, and the layer of brick *t* between the apron *g'* and the base of the shell, substantially as herein described.

30. 12. In an ore-smelting furnace, the shell *T*, having an encircling-flange, *s*, near its top, in combination with the supporting-pillars *V*, and the wind-chamber *S*, triangular in cross-section, said wind-chamber encircling, though 35 independent of, the shell and forming a hollow girder resting on the pillar and supporting the flange *s* whereby the shell is supported, substantially as herein described.

13. In an ore-smelting furnace, the base-plate

40 B and crucible base-wall *A*, and the hydrocycle *G* surrounding the region of fusion and resting on wall *A*, said hydrocycle consisting of independent and separately-removable cells or compartments *g*, bound together to form a rigid trough, in combination with the shell *T* 45 having the flange *s* and independent wind-chamber *S*, triangular in cross-section and encircling loosely said shell, and the pillars *V* resting on the base-plate and bearing under the wind-chamber, whereby said chamber is 50 supported without resting on the hydrocycle, substantially as herein described.

14. In an ore-smelting furnace, the shell *T*, the upper and greater portion of which has the shape of an inverted truncated cone, its 55 exterior and interior surfaces being parallel, and the lower and smaller portion of which flares outwardly to form a return slope at *U*, just above the region of fusion of the furnace, substantially as herein described. 60

15. In an ore-smelting furnace, the shell *T*, the upper and greater portion of which has the shape of an inverted truncated cone, its interior and exterior surfaces being parallel, and the lower and smaller portion of which 65 flares outwardly to form a return slope at *U*, just above the region of fusion, in combination with the hydrocycle *G* below the return slope and surrounding the region of fusion, and the tuyeres *P*, all arranged and operating, substantially as herein described. 70

In witness whereof I have hereunto set my hand.

EDWARD PROBERT.
